R. G. SCOTT

WRENCH

Filed April 1, 1924

By *Clarissa C. O'Brien*
Attorney

Patented June 9, 1925.

UNITED STATES PATENT OFFICE.

RICHARD G. SCOTT, OF EDMONTON, ALBERTA, CANADA.

WRENCH.

Application filed April 1, 1924. Serial No. 703,429.

To all whom it may concern:

Be it known that I, RICHARD G. SCOTT, a subject of the King of Great Britain, residing at Edmonton, in the Province of Alberta and Dominion of Canada, have invented certain new and useful Improvements in Wrenches, of which the following is a specification.

This invention relates to new and useful improvements in wrenches, and has for its principal object to provide a simple and efficient device which may be used either in connection with objects having round or square or flat surfaces.

15 A further object of the invention is to provide a wrench of the above-mentioned character, whereby the same may be easily and quickly adjusted to the desired size of objects upon which the same is to be used, 20 means being further provided for holding the slidable jaw of the wrench in its proper adjusted position against accidental displacement while the same is in use.

Other objects and advantages of this invention will become apparent during the course of the following description.

In the accompanying drawing forming a part of this specification, and in which like numerals designate like parts throughout 30 the same,

Figure 1 is a side elevation of my invention with parts shown in section,

Fig. 2 is an end elevation thereof,

Fig. 3 is a vertical section taken on line 35 3—3 of Fig. 1,

Fig. 4 is a detail view of one of the spring fingers, and

Fig. 5 is a transverse section taken approximately on the line 5—5 of Fig. 1.

40 In the drawing wherein for the purpose of illustration is shown the preferred embodiment of my invention, the numeral 1 designates an elongated shank the lower end of which is reduced as shown at 2 in the drawing to receive a suitable handle 3. Formed on the upper end of the shank 1 is the stationary jaw 4 which includes the extensions 5 and 6, respectively. The bottom surface of the extension 5 is serrated as shown at 7 while the bottom surface of the extension 6 is substantially smooth as shown at 8 in the drawing. The purpose of this construction will be hereinafter more fully described. Provided in the side faces or 50 edges of the shank 1 for its entire length between the stationary jaw and the upper

portion of the handle 2 are the transversely arranged serrations 9 and 10, respectively.

Slidably supported on the shank 1 and adapted for longitudinal movement thereon 60 between the stationary jaw and the upper end of the handle is the slidable jaw 11. This slidable jaw 11 has extensions 12 and 13 formed on the upper portion thereof which are adapted to coact with the extensions 5 and 6 formed on the stationary jaw 4 and the upper surface of the extension 12 is provided with serrations 14 which co-operate with the serrations 7 and the extension 13 has its upper surface substantially 70 smooth as illustrated at 15 to co-operate with the smooth surface 8 of the extension 6 of the stationary jaw 4. The side walls of the opening 16 extending through the slidable jaw 13 whereby the same may be 75 supported on the shank 1 are also provided with transversely arranged serrations such as are shown at 17 to co-operate with the serrations 9 and 10, respectively, formed in the side edges of the shank 1.

80 Arranged on the front and rear faces of the shank 1 and extending longitudinally thereon are the nurled or milled surfaces such as are shown at 18 in the drawing. The purpose of this construction will be 85 presently apparent. Formed in the front and rear faces of the slidable jaw 11 and extending inwardly from opposite sides thereof are the cutout portions or grooves 19 and 20, respectively. The cutout portions extend transversely through the opening 16 and have their inner ends communicating therewith in the manner as clearly shown in Fig. 5 of the drawing.

90 Adapted to be detachably supported in each of the cutout portions is the spring finger 21 the outer end of each finger having an opening 22 formed therein whereby the fastening screw 23 will extend therethrough and support the same in each 100 groove formed in the slidable jaw. The inner end of each of the spring fingers is enlarged as shown at 24 and the inner surface of the enlarged portion 24 of each finger is also nurled or milled to co-operate with the nurled or milled surfaces 18 on the front and rear sides of the shank 1 in the manner as clearly shown in Fig. 5 of the drawing.

105 The nurled surfaces 25 of the spring fingers 21 will normally be in engagement with the nurled surfaces 18 of the shank 1 and provides a means for holding the slidable

jaw lever in its adjusted position on the shank 1. The extension 5 and the co-action extension 12 which have their inner opposed faces provided with serrations are adapted 5 to be used when the wrench is placed on round objects such as pipes or the like, while the smooth inner opposed surfaces of the opposite extension are used in connection with objects having flat surfaces such as nuts or 10 the like.

With the wrench of the above-mentioned character, the slidable jaw may be easily and quickly adjusted to the proper size and the spring finger 21 will hold the slidable jaw 15 in its proper adjusted position and against accidental displacement on the shank when the object which is being turned by the wrench is in position therein. The simplicity of my device enables the same to be manufactured at a very low cost and does not 20 require the use of a complicated number of parts in order to hold the slidable jaw in its proper adjusted position.

While I have shown the preferred embodiment of my invention, it is to be understood that various changes in the size, shape, and arrangement of parts may be resorted to 25

without departing from the spirit of the invention and the scope of the appended claim.

Having thus described my invention, what 30 I claim is:

A wrench comprising a shank having a jaw fixed thereto, said shank having rectangularly disposed side surfaces, the opposite side surfaces being disposed parallel 35 with relation to each other, two of the opposite side surfaces being nurled, and the other two intervening side surfaces being milled, a jaw movably mounted upon the shank and having an opening which loosely receives 40 the shank, two of the opposite wall surfaces of the openings being provided with serrations adapted to engage the milled surfaces of the shanks, the said movable jaw being provided at its intervening sides with slots 45 leading in from opposite edges of the said movable jaw, and spring fingers secured to the movable jaw and extending along the slot and having nurled surfaces adapted to resiliently engage the nurled surfaces of 50 the shank.

In testimony whereof I affix my signature.

RICHARD G. SCOTT.
